UNITED STATES PATENT OFFICE.

ARTHUR A. ARNOLD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

CUTTER.

1,230,551.

Specification of Letters Patent. Patented June 19, 1917.

Application filed January 9, 1917. Serial No. 141,431.

To all whom it may concern:

Be it known that I, ARTHUR A. ARNOLD, a citizen of the United States, residing at Southbridge, in the county of Worcester and 5 State of Massachusetts, have invented certain new and useful Improvements in Cutters, of which the following is a specification.

My invention relates to improvements in 10 cutters and has particular reference to that type of cutter adapted for cutting ophthalmic lenses or the like in oval and other varying shapes.

One of the leading objects of the present 15 invention is the provision of an improved cutter which shall be substantially complete in itself and may be used to cut a maximum number of varying shapes and sizes of lenses without the necessity for multiplicity of adjustments and re-arrangement of the parts, 20 or substitution of parts, as is at present the common practice.

A further object of the present invention 25 is the provision of a construction which may be readily employed for cutting various lens surfaces or the like, that is to say, such as plano concave or convex surfaces, with the same cutting point.

A further object of the present invention 30 is an increased simplification of the several parts of a lens cutter coupled with an increased efficiency of operation.

Other objects and advantages of my improved construction should be readily apparent by reference to the following specification taken in connection with the accompanying drawings forming a part thereof, and it will be understood that I may make any modifications in the specific details of 40 construction shown and described within the scope of the appended claims without departing from or exceeding the spirit of my invention.

Figure I represents a perspective view of 45 a complete cutter embodying my several improvements.

Fig. II represents a detail perspective view of the contact shoe.

Fig. III represents an enlarged detailed 50 view of the scale or vernier for use in connection with my improved adjustable diamond.

Fig. IV represents a similar view of a modified construction.

Fig. V represents a detailed view of a 55 slightly modified construction of adjustable diamond support.

Fig. VI represents a sectional view thereof.

Fig. VII represents a further modification of my construction.

In the drawings, in which similar characters of reference are employed to denote corresponding parts throughout the several views, the numeral 1 designates the base of 65 my improved cutter, having rising therefrom the pedestal 2, on which is rotatably mounted the lens supporting table 3, adapted to be rotated by turning of the handle 4 on the gear 5 which is supported above the 70 table 3 by the bracket 6 on the standard 7, a shaft 8 being journaled in the standard 7 and having pinions on its opposite ends meshing respectively with the toothed edge of the table 3, and the teeth of the gear 5 to 75 cause synchronous rotation of these parts, the foregoing parts being of substantially well known construction and forming no special novel portion of my invention, except in so far as the novel features of my invention are particularly adapted for co-operation and enter into combination with the foregoing parts.

As is the well known practice in connection with lens cutters, a suitable clamp 9 is 85 preferably provided for retaining the lens in position on the table, while an arm or frame 10 is pivoted to the standard 7 and provided with former engaging portions and with a cutter for operating upon the lens. 90

Prior to my invention, however, it has been customary to provide a suitable former rotating synchronously with the lens on the lens table, a plurality of interchangeable formers ordinarily being employed and 95 adapted to be substituted one for the other on the former bearing spindle 11 according to the particular shape desired. In addition it has been customary in the past to provide the pivoted arm or frame 10 with a pair 100 of spaced former engaging shoes and to regulate the relative dimensions of the shape produced by separation or bringing together of the shoes and additionally to correspondingly vary both the major and minor axes of 105 the shape by moving the contact shoes in or out relative to the pivoted arm 10.

It is, therefore, one of the essential pur-

poses of my present invention to do away with the interchangement of parts and to reduce to a minimum the adjustment to be made. In the accomplishment of this result 5 I have secured on the spindle 11 in place of a single former, a battery of formers 12, embodying the different sizes and shapes commonly employed in cutting lenses, while for coöperation with this battery of formers, I 10 have rotatably mounted in the upper portion of the arm or frame 10, the spindle 13, bearing at one end the knurled indicator 14 and at the other end the contact head 15. This contact head, as is most clearly shown 15 in Fig. II, is provided on its face with the irregularly shaped star wheel projecting rib 16, the various portions of the rib 16 being disposed at different distances from the point of rotation or axis of the spindle 13 20 so that turning of the head 15, as by manipulation of the knurled operating portion 14, will selectively engage different portions of the rib with different formers, suitable designations, as the numerals 17, on the knurled head 14 indicating which particular former the rib is engaging for any particular adjustment of the parts. It is to be understood 25 that the thickness or distance from the face of the rib 16 to the head 15 is sufficient to at all times maintain the head 15 out of engagement with the series of forms or formers 12, irrespective of the adjustment of the rib to engage any particular former, such as the lowest or smallest one, so that the head 30 will at all times exactly follow the particular former selected.

While it will be understood in connection with the present invention that the in and out adjustment may if desired be applied 40 either to the contact shoe or to the diamond, I have found that for convenience of construction and manipulation of the parts it is preferable to apply this adjustment to the diamond or cutting point. In carrying out 45 this portion of my invention I form the lower part of the arm or frame 10 with the enlargement 18, in which is slidably mounted the carrier bar 19, whose position is controlled by the adjusting screw 20 having 50 the knurled operating head 21. This carrier bar 19 has pivoted to its inner end or adjustably supported thereby, the cutter head 22, which is provided with a suitable cutting point 23.

55 The desirability of the tiltable diamond will be readily apparent to all conversant with the art of cutting lenses, since it is a well known fact that to secure best and most satisfactory results it is desirable that the 60 diamond be placed normal to the surface being operated upon whether concave, convex or plano, which result can be readily accomplished with my improved rotating head 22. As indicated in the drawing the 65 head 22 may be provided with a plurality

of sockets 24 or the like, adapted to receive the end of the latch member 25 to lock the head in any desired adjusted position.

In the form illustrated in Fig. I it will be noted that the position of the diamond 70 relative to the lens is somewhat varied in a setting from concave to convex cutting position, due to the center about which the head 22 turns.

In order that allowance may be readily 75 made for this feature I have found a very simple and convenient way of indicating the size and at the same time making allowance for the angle at which the cutter is set. In the indicating of the in and out adjustment 80 of the point of the diamond combined with the compensation for tilting of it, I preferably form on the bar 19 a rack 26 adapted to mesh with the indicator pinion 27 which bears on its upper end the collar 28 provided 85 with the central graduation 29 for plano position, and the side graduations 30 and 31 for convex and concave, respectively. The micrometer scale plate 32 is secured on the bracket 18 and locked in adjusted position 90 as by the screw 33, thus permitting of adjustment of the scale as an entirety to take care of wear or the like. The operation of this scale should be readily understood and it will be seen that upon rotation of the 95 adjusting screw 20 by means of the head 21 the in and out movement of the bar 19 will, through the rack and pinion, rotate the collar 28, and the adjustment can be read off by comparing the proper indicating lines 100 29, 30 or 31, with the scale on the plate 32, which will indicate the exact position of the point with respect to the edge of the particular former being employed, that is to say whether it is at a position to cut the 105 same size as the size of the former or a size greater than or less than that of the former.

In Fig. IV, I have illustrated an alternate construction to Fig. III, in which in place of having the three lines from which to take 110 readings I have merely the central line 29, the plate 32 being held by a thumb screw 33 in place of a plain screw and being adapted to be self-adjusted according to the adjustment given to the cutting point. If 115 desired this feature may be taken care of automatically, however, as illustrated in connection with Fig. VII, in which a construction similar to Fig. IV is shown, with the exception that the screw 33 is eliminated 120 and in place of the screw the rotated position of the plate 32 is controlled by the pin 33 on the extension of the latch 25, while the depth of notches or sockets 24 in the head 22 in which the latch fits is so adjusted that 125 when the latch strikes the bottom of the socket to lock the head in either of its three adjusted positions the plate will have been automatically shifted to give the correct reading.

In Figs. V and VI, I have illustrated a further modification of my diamond point, in which the bar 19 is provided with an arcuate groove, in which rides an arcuate head 22', the curvature of the groove and head being about the point of the diamond as a center so that the position of the point remains unvaried for the several adjustments to accommodate the different forms 10 of lenses.

From the foregoing description taken in connection with the accompanying drawings, the construction and operation of my improved cutter should be readily apparent, and it will be seen that I have provided a simple and durable machine, in which a battery of formers is employed in connection with means for selectively engaging the formers, whereby any desired 15 shape may be attained without the necessity for interchangement of formers as has hitherto been required, and it will further be noted that my single diamond may be readily set to cut any desired curvature of surface 20 and that I have provided means which may be either manual or automatic in character for taking care of the variance, if any, in position of the diamond point so that the correct reading may be accurately obtained 25 from the scale irrespective of the particular adjustment of the point.

I claim:

1. A lens cutter, including a rotatable table and a spindle rotatable therewith, a 30 battery of formers on the spindle, a cutter bearing arm, and means on the arm for selectively engaging the formers to control the shape outlined by the cutter.

2. In a lens cutter, the combination with 35 the cutter table and a guiding former, of a pivoted cutter arm, means on the arm for engaging the guide former, a shiftable bar carried by the arm, and a cutting point carried by the arm and angularly adjustable 40 relative thereto.

3. A lens cutter, including an angularly adjustable cutting point, means for transversely shifting the cutting point, means for indicating the amount of transverse shifting 50 of the cutting point, and means for compensating on the indicating device for the angular adjustment of the cutter.

4. In a lens cutter, the combination with 55 a cutter arm, of a transversely slidable bar carried by said arm, means for transversely shifting the bar, a cutter point adjustably mounted on the bar, and means for indicating the adjustment of the bar and cutter.

5. In a lens cutter, the combination with 60 a rotatable table and synchronously operating spindle, of a battery of formers carried by the spindle, a cutter arm, means on the

cutter arm for selectively engaging the formers, a transversely shiftable cutter carried by the arm, means for shifting the cutter, and means for indicating the adjustment of the cutter relative to the edge of the selected former. 65

6. In a device of the character described, the combination with a lens supporting table, of a battery of formers arranged concentric therewith, a cutter arm, a contact head carried by the cutter arm having a series of eccentrically arranged ribs adapted for selective engagement with the several formers 70 of the battery, means for indicating the adjustment of the contact head, and a cutter carried by the arm and shiftable therewith and with respect thereto for operatively engaging a lens on the table. 75

7. A lens cutter, including a table and a battery of formers arranged concentric therewith, a cutter arm, a contact head carried by the arm and having portions for selectively engaging the several formers of the 80 battery, a cutter, and means for relatively adjusting the head and cutter to vary the size of the selected form which is inscribed on the lens. 85

8. In a lens cutter, the combination with 90 the cutter arm, of a bar slidable in the arm, a cutter carried by the bar, a rack on the bar, a pinion carried by the arm and meshing with the rack whereby shifting of the arm rotates the pinion, and a coöperating 95 scale and indicator on the arm and pinion for indicating the adjustment of the bar and cutter.

9. In a lens cutter, the combination with a cutter arm, of an angularly adjustable cutter carried thereby, means for varying the transverse position of the cutter for a given adjustment, a scale and indicator for registering the transverse adjustment of the cutter, and means for varying the position of 100 one of the two last named parts to compensate for angular adjustment of the cutter. 105

10. In a lens cutter, the combination with the cutter arm, of an angularly adjustable cutter carried thereby, means for transversely shifting the cutter with respect to the surface to be operated upon, means for indicating the amount of transverse shift, and an automatic compensating device operable by the angular adjustment of the cutter 110 for adjusting the scale according to the angular position occupied by the cutter, substantially as and for the purpose described. 115

In testimony whereof I affix my signature in the presence of two witnesses.

ARTHUR A. ARNOLD.
